(57) **CLAIM**

The ornamental design for an inflatable cushion, as shown and described.

DESCRIPTION

FIG. 1 is a perspective view of an inflatable cushion showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Any shading in the form of contour lines are not features of the design but are utilized to illustrate the surface contours of the inflatable cushion design in the drawings.
